WALKING HEEL FOR PLASTER CASTS

Howard W. Blosser, 2418 Wall St., Joplin, Mo. 64801
Filed July 15, 1964, Ser. No. 382,827

3 Claims. (Cl. 128—83.5)

This invention relates to new and useful improvements in walking heels adapted for use by ambulatory patients having a foot and ankle encased in a plaster cast, such walking heels commonly being affixed to the sole of the foot portion of the cast in order to facilitate walking.

The principal object of the present invention is the provision of a walking heel of the character described having novel means for insuring its proper placement with respect to the normal support line of the patient's leg, whereby to provide greater ease and comfort in walking. The normal shape and contour of the patient's foot is often so concealed and camouflaged by the cast that the heel is applied slightly out of proper position, with the result that balancing and walking thereon is difficult and uncomfortable.

Another object is the provision of a walking heel of the character described which eliminates the necessity of building up the sole surface of the cast to a flat, planar contour preparatory to applying the walking heel thereto, whereby application of the heel is rendered faster, simpler and more convenient.

A further object is the provision of a walking heel of the character described which, while secured to the cast with additional plaster in the conventional manner, may be so secured with a smaller amount of additional plaster than has heretofore been possible, thereby reducing the total weight of heavy casts. This weight reduction is of course very important to ambulatory patients, to whom the weight of heavy casts is very fatiguing.

Other objects are simplicity and economy of construction, efficiency and dependability of operation, and ease and convenience of usage.

With these objects in view, as well as other objects which will appear in the course of the specification, reference will be had to the accompanying drawing, wherein:

FIG. 1 is a side elevational view of a patient's foot and lower leg encased in a plaster cast, and having a walking heel embodying the present invention applied thereto, portions of the plaster cast being broken away,

FIG. 2 is a sectional view taken on line II—II of FIG. 1,

FIG. 3 is a top plan view of the walking heel,

FIG. 4 is a side elevational view of the walking heel, partially broken away,

FIG. 5 is an end elevational view of the walking heel, and

FIG. 6 is an inverted plan view of the walking heel.

Like reference numerals apply to similar parts throughout the several views, and the numeral 2 applies to a patient's foot and lower leg to which a plaster cast 4 has been applied in the ordinary way. Usually, the plaster is supplied impregnated in a crinoline textile bandage which is first thoroughly wetted, then wrapped evenly about the foot and leg to a substantially uniform thickness, and allowed to set. Since it is of uniform thickness it follows the contour of the foot. Insofar as the present invention is concerned, the salient point here involved is that the instep 6 of the cast has a concave contour more or less faithfully following the contour of the instep 8 of the patient's foot.

The walking heel forming the subject matter of the present invention is designated generally by the numeral 10, and constitutes a single integral mass of rubber or other suitable resilient material. It includes a rectangular planar platform 12 adapted to be placed against the

2

sole of cast 4 with its major dimension disposed longitudinally of the foot, a cleat 14 depending from said platform, and a rounded protuberance 16 projecting upwardly from the top surface of said platform.

5 Cleat 14 is of the same width as platform 12, which is somewhat narrower than the patient's foot, and is elongated longitudinally of the platform, being shorter than the platform and disposed centrally between the ends thereof, whereby the end portions of said platform constitute lips 18 facilitating attachment of heel 10 to cast 4, as will presently appear. Also, cleat 14 is divided midway between its forward and rearward ends by a transverse slot 20. The lower end surface of the cleat is convexly curved about a horizontal axis disposed transversely to an well above platform 12, in order to permit the cleat to "roll" on the floor as the patient walks. Said convex cleat surface also has ridges 22 formed therein to provide a non-skid grip on the floor. Said ridges may be of any desired pattern.

20 Protuberance 16 on the top surface of platform 12 is convexly rounded in contour, being thickest at the midpoint of one of the longer edges of the platform, and being centered between the forward and rearward ends of said platform. Transversely, it extends slightly more than half the width of the platform.

25 In application, the walking heel is placed against the sole of cast 4, with protuberance 16 engaging in instep contour 6 of the cast, and is secured in place by plaster 24, usually in the form of plaster bandage wrapped about cast 4 so as to pass under lips 18 and through notch 20 of the heel. After plaster 24 has been allowed to set, the patient may walk. In FIGS. 1 and 2, plaster 24 has been cross-hatched to distinguish it from the plaster of cast 4, to indicate that it is applied at a different time. 30 However, it will be understood that once plaster 24 has been applied, it forms an integral mass with cast 4.

35 The walking heel thus described will be seen to possess several novel advantages as compared to prior walking heels, these advantages being provided by the protuberance 16. Firstly, the engagement of said protuberance in the instep contour 6 of cast 4 provides automatically for proper placement of the heel directly in line with the normal support line S—S of the patient's leg, this line being centered with respect to the instep as indicated in FIG. 1. 40 This alignment is very important, since even relatively slight errors in the placement of the heel can result in considerably muscle strain, discomfort and fatigue to the wearer. In all prior walking heels within my knowledge the upper surface of the platform thereof has been planar, and it has been common practice to build up cast 4 to provide a planar surface for engaging and properly supporting said platform. The heel was then placed almost necessarily by eye, since the exact position and shape of the foot was largely camouflaged by the cast, 45 and such placement was often inaccurate. Such heels were often accompanied by such vague instructions as "place the heel slightly behind the center of the cast." My protuberance 16 provides quite automatically for proper positioning of the heel.

50 Secondly, with the prior art heels having platforms with planar upper surfaces, the necessary building-up of the sole of the cast to a planar configuration to provide solid support for the platform was a rather tedious process usually accomplished by filling in the instep cavity 6 with a shaped wadding of plaster bandage, and securing said wadding in place with additional plaster bandage wrapped about the body of the cast. All necessity for this time-consuming step is eliminated by the 55 protuberance 16 of the present heel, and may heel therefore may be applied much more rapidly and conveniently.

Thirdly, the "filling-in" or "levelling" process described above necessarily involves the addition of considerably more plaster to the cast than just the wadding required to fill the instep contour, the excess being the plaster required to fix the wadding in place. Plaster is of course heavy, and any excess plaster simply increases the total weight of the cast, which the patient must of course lift and carry as he walks. Therefore, since the present heel eliminates the necessity of the cast "levelling," it permits the use of a lighter weight cast which is correspondingly less fatiguing to the patient.

While I have described and claimed a specific embodiment of my invention, it will be readily apparent that many minor changes of structure and operation could be made without departing from the spirit of the invention as defined by the scope of the appended claims.

What I claim as new and desire to protect by Letters Patent is:

1. A walking heel for plaster casts comprising a one-piece integral member formed of resilient material and including:

- (a) a generally planar and rectangular platform adapted to be positioned and secured against the sole of plaster cast encasing a patient's foot, beneath the concave instep contour of said cast, and with its major axis extending parallel to the longitudinal mid-line of the foot,
- (b) a ground-engaging cleat depending from said platform, and
- (c) an upwardly convex protuberance on the upper surface of said platform and shaped to engage snugly in the instep contour of the sole of said cast, whereby

said cleat is positioned longitudinally of the wearer's foot in positive relation to the transverse vertical plane of this weight-support line of the wearer's leg.

- 2. A walking heel for plaster casts as recited in claim 1 wherein the lower or ground-engaging surface of said cleat is downwardly convex, being curved about an axis parallel to the minor axis of said platform, whereby only a limited area of said lower cleat surface engages the ground at any one time.
- 3. A walking heel for plaster casts as recited in claim 1 wherein the lower or ground-engaging surface of said cleat is downwardly convex, being curved about an axis parallel to the minor axis of said platform, whereby only a limited area of said lower cleat surface engages the ground at any one time, and wherein the transverse vertical plane of said platform including the lowermost point of the convex curvature of said lower cleat surface is coincident with the transverse vertical plane of the platform including the thickest portion of said protuberance, whereby the lowermost point of said lower cleat surface is aligned with the weight-support line of the wearer's leg.
